Primary Examiner — Manpreet S Matharu*Assistant Examiner* — Mojtaba Tehrani(74) *Attorney, Agent, or Firm* — McDonnell Boehnen
 Hulbert & Berghoff LLP(57) **CLAIM**

The ornamental design for an adjustable cheek riser, as shown and described.

DESCRIPTION

FIG. 1 is a perspective view of an adjustable cheek riser showing my new design;

FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof; and,

FIG. 8 is another perspective view thereof.

The broken lines illustrate portions of the drawings that form no part of the claimed design.

1 Claim, 4 Drawing Sheets(56)
